US0D1022144S

(12) **United States Design Patent** (10) **Patent No.:** **US D1,022,144 S**
(45) **Date of Patent:** **** Apr. 9, 2024**

(54) **TUB SPOUT**

(71) Applicant: **ASSA ABLOY Americas Residential Inc.**, New Haven, CT (US)

(72) Inventor: **Bingo Wang**, Xiamen (CN)

(73) Assignee: **ASSA ABLOY Americas Residential Inc.**, New Haven, CT (US)

(**) Term: **15 Years**

(21) Appl. No.: **29/796,626**

(22) Filed: **Jun. 25, 2021**

(51) LOC (14) Cl. **23-01**

(52) U.S. Cl.

USPC **D23/257**

(58) **Field of Classification Search**

USPC D23/238-244, 252, 254-255, 257, 499;

(57) **CLAIM**

The ornamental design for a tub spout, as shown and described.

DESCRIPTION

FIG. 1 is a front perspective view of a tub spout showing my new design;

FIG. 2 is a left side view thereof;

FIG. 3 is a right side view thereof;

FIG. 4 is a front view thereof;

FIG. 5 is a top view thereof;

FIG. 6 is a bottom view thereof;

FIG. 7 is a front perspective view of the tub spout of FIGS. 1-6 shown without disclaimed regions;

FIG. 8 is a left side view thereof;

FIG. 9 is a right side view thereof;

FIG. 10 is a front view thereof;

FIG. 11 is a top view thereof; and,

FIG. 12 is a bottom view thereof.

The broken lines immediately adjacent to the photographic area define the bounds of the claimed design and form no part thereof. The unshaded areas within the broken lines form no part of the claimed design.

1 Claim, 12 Drawing Sheets
